United States Patent Office

Des. 177,660
Patented May 15, 1956

177,660

COMBINED PENCIL HOLDER AND ADVERTISING DEVICE OR THE LIKE

Matthew B. Blish, Oak Park, Ill.

Application June 1, 1953, Serial No. 25,257

Term of patent 3½ years

(Cl. D74—1)

Fig. 1.

Fig. 2.

Fig. 3.

Fig. 4.

Fig. 5

Fig. 1 is a front elevational view of a combined pencil holder and advertising device or the like, showing my new design;

Fig. 2 is a side elevational view of the same;

Fig. 3 is a rear elevational view;

Fig. 4 is a bottom plan view, and

Fig. 5 is a cross-sectional view thereof taken on line 5—5 of Fig. 1.

I claim:

The ornamental design for a combined pencil holder and advertising device or the like, substantially as shown.
